UNITED STATES PATENT OFFICE

CALVEN AERICK, OF LOS ANGELES, CALIFORNIA

UNIVERSAL NURSING STAND

Application filed March 13, 1929. Serial No. 346,763.

This invention relates to means for holding a nursing bottle and has for an object to provide a simple, practicable and inexpensive stand which may be readily fixedly or removably attached to one or another of various types of supports such, for instance, as the back rail of a high chair, the rail of a crib, or of a cradle, or the basket of a baby carriage.

A further object is to provide a universal bottle clamping swing and to provide means for automatically carrying the swing off to one side and away from the face and head of the baby and yet allow a quite young infant to easily grasp and bring the milk bottle over to a comfortable position at its mouth.

The general object of the invention is to relieve the mother, the nurse or other attendant of the burden of closely watching the baby to see that it does not cast the bottle, if free, away with destructive results and also a purpose is to have the bottle handily mounted so that the baby may have milk as its appetite, notion or whim may demand to the end that the peace of all may be conserved and at the same time leave the attendant free to attend to other duties and not be solely mindful of the infant.

Additionally an object is to provide for the compact packaging of the device and for its being kept in a clean and wholesome condition by reason of the simplicity of its structure and fewness of its parts.

Numerous other objects, advantages and features will be made manifest in the following description of the herewith illustrative embodiment; it being understood that modifications, variations and adaptations may be resorted to within the spirit, scope and principle of the invention as it is more directly hereinafter claimed.

The figure is a perspective of the stand as mounted.

The bottle swing includes a set of side bars 2 of suitable material, as enameled or nickel plated wire. One end of each bar is connected to an elastic girdle 3 preferably made of a helical spring. This is somewhat smaller in diameter than a second or body band 4 also made of helical spring and being suitably attached to the bars 2 at points near their bot-

tom ends; these being hooked inward to grapple around the bottom of an inserted bottle B.

The forward ends of the swing bars bend inward to fit around the neck of the bottle. It will be seen that the spring girdles 3—4 will readily adapt themselves to bottles of different sizes and cross-sectional forms, as may be preferred in the household or the nursery.

One of the bars is attached to a suitable chain 6 which may be hooked at suitable height on a hook 7 carried by the overhead arm of a crane whose standard is preferably made of sections 9—9^a connected by a slip joint tube 10 fixed on the section 9^a.

The standard is turnably supported on a bracket 11 which is shown as having a plate 12 to be fastened by screws, as to the back of a baby-chair C. The bracket has a shelf with spaced stop lugs 13 to engage a contact part on the standard and which is here shown as a short foot 14. To give the crane an automatic outward action from the baby's face when the bottle is released a cam leaf 15 is punched up from the shelf and the foot 14 slides to and fro on this cam; the lugs on the end of the leaf limiting the movement.

If desired the bracket may have a hanging wall 16 with an inner spring jaw 17 which will firmly frictionally grip a part on which the bracket may be slipped into place. This eliminates screws.

What is claimed is:

1. A nursing bottle stand having a supporting bracket, a crane standard mounted on the bracket to swing horizontally, means to limit movement of the crane, a bottle swing suspended by a flexible connection from the crane, and a cam device to impel the crane in one direction.

2. A nursing bottle stand having a supporting bracket, a crane standard turnably mounted on the bracket, a bottle swing suspended by the crane, and a cam leaf to impel the crane in one direction and having lugs to limit movement of the crane in either direction.

3. A nursing bottle swing including a pair of side bars whose upper ends are connected by a loop formed of a helical spring adapted

to close around the shoulder of a bottle, the opposite ends of the bars being inturned toward each other, and a helix-spring band connecting the inturned ends of the bars; 5 whereby in application of the swing to a bottle the inturned ends are spread to freely pass down over the neck and body of the bottle and then will snap into embracing position with the hooks under the bottom of 10 the bottle.
